UNITED STATES PATENT OFFICE.

JOHN WM. CUPPY, OF BALTIMORE, MARYLAND.

MOP-WRINGER.

1,147,612.

Specification of Letters Patent. Patented July 20, 1915.

Application filed June 25, 1912. Serial No. 705,802.

To all whom it may concern:

Be it known that I, JOHN WILLIAM CUPPY, a citizen of the United States, residing at Baltimore, in the State of Maryland, have 5 invented new and useful Improvements in Mop-Wringers, of which the following is a specification.

This invention relates to a mop wringer.

An object of the invention is to provide 10 means for wringing the mop fabric and for conveniently permitting said fabric to be readily returned to its initial position after it is wrung.

Another object of the invention is to provide 15 means for wringing means which will comprise companion elements that are operatively connected with each other without the use of such permanent fastening devices as screws, bolts or the like.

20 In the drawing forming a portion of this application, and in which like letters of reference indicate similar parts in the several views:—Figure 1 is a side elevation showing the mop in operative position. Fig. 2 is a top plan view. Fig. 3 is a side view showing 25 the mop in wringing position. Fig. 4 is a section on line 5—5 of Fig. 1. Fig. 5 is a perspective view of the ratchet wheel. Fig. 6 is a view showing the manner of bending 30 the actuating portion of the wringer whereby to secure the terminal of said portion to the ratchet wheel.

The wringer is used in connection with such a well known form of mop as shown 35 herein provided with a handle 1 having a bearing 2 provided with trunnions 3 for supporting the foot 4 having eyes 7 and yoke 6.

40 The wringer consists of a bracket 12, which is provided with a lateral branch 13 and a brace arm 14 as shown. The branch portion 13 and the brace arm 14 terminate in a bearing 15 which is longitudinally disposed with relation to the handle 1. The 45 wringing element is constructed of a single length of wire whose intermediate portion 16 is extended through the bearing 15 so as to freely revolve therein while the lower terminal is disposed beneath the bearing and 50 bent to present a substantially triangular portion 17 which is associated with the upper fold of the mop fabric. The portion 17 has a branch 18 which is abruptly extended away from the intermediate portion 16 of 55 the wringing element so as to form a stop at 19 to hold said element against sliding

movement in one direction in the bearing. A ratchet wheel 20 is seated upon the upper end of the bearing 15, being adapted to revolve thereon and to receive the upper end 60 of the intermediate portion 16 of said wringing element. Said ratchet wheel is provided with an integral lug 21 which has a recess 22 therein, the latter being bounded or defined by spaced inner walls 23 and a single connecting end wall 24 so that one side of the boss is open as at 25. The upper terminal of the wire forming the wringing element is bent to provide a triangular actuating hand grip 26 having a branch 27 which extends 70 through the recess 22 and braced by the wall 24 and associated therewith in such manner that the wall will form a stop to hold the wringing element against movement in another direction in the bearing 15. The grip 75 26 is also provided with a branch 28, which extends through the recess in the boss and which is positioned between the walls 23 and terminally disposed immediately adjacent the open side 25 of the boss. The branch 28 80 may be readily bent into the recess when initially assembling the hereinbefore parts of the wringer. Said branch 28 and the companion branch 27 both form a key for holding the ratchet wheel against rotation 85 independently of the wringing element.

A stud 29 upon the branch arm 14 of the bracket 12 pivotally supports a dog 30. This dog has its nose 31 associated with the 90 ratchet wheel so as to engage the teeth thereof to hold the wringing element against retrograde rotation when wringing the cloth. The tail 32 of the dog and the arm 14 have interposed therebetween a spring 33 whereby the nose of the locking dog will be yieldingly held operatively engaged with the teeth of the ratchet wheel. The tail of the dog terminates in juxtaposition with the handle 1 whereby it can be conveniently engaged by the hand of the operator when desired. By constructing the wringing element whereby it will be positively held 95 against sliding longitudinally in the bearing 15 it becomes evident that the ratchet element will be held against being accidentally disconnected from the locking dog.

I claim:—

1. In a mop wringer, a handle, a foot pivoted thereto, a bracket extending laterally from the handle and provided with a bearing extending longitudinally with the handle, a ratchet element rotatably mounted 110

upon the bearing, provided with an integral boss, having a recess bounded by two sides and one end wall, said sides being spaced apart a distance substantially equal to the 5 diameter of the wire of which the wringer element is constructed, a wringer element having a portion mounted to rotate in said bearing, and a portion below the bearing to which a mop cloth can be attached, a grip 10 formed on the element above the bearing and having two angularly disposed branches extending through the recess in the boss, one of the branches terminating at its free end immediately adjacent the open side of the 15 recess and means engaging the ratchet element to hold the same against rotation in one direction.

2. In a mop wringer, a handle, a foot carried by said handle, a bracket extending 20 laterally from the handle and provided with a bearing which extends longitudinally with the handle, a ratchet element rotatably mounted upon the bearing, a wringer element constructed of a single length of wire 25 bent to provide a cloth attaching portion below the plane of the bearing and an actuating portion above the plane of the bearing,

and an intermediate portion through the bearing and through the ratchet element the 30 said attaching portion having a branch abruptly extending from beneath the bearing and associated therewith so as to form a stop to hold the wringing element against movement in one direction in the bearing, the boss having a recess bounded by two side 35 walls and a single end wall, said side walls being spaced apart a distance substantially equal to the diameter of the wire of the wringer element is constructed, the said actuating portion of the wringer element 40 having a branch extended through the recess of the boss and a second branch portion terminating at its free end immediately adjacent the open side of the recess and extended into said recess and disposed against 45 the spaced side walls and means engaging the ratchet element to hold the same against rotation.

In testimony whereof I affix my signature in presence of two witnesses.

JOHN WM. CUPPY.
